S. Richards,

Knob.

Patented Oct. 31, 1831.

and of great value to the Poor and Working
Classes, and of great assistance in the work of the
Church, and of great encouragement in working up the
cause of the Poor and Working Classes.

Not having been able to get a license of Cambridge in the County of
Essex, I have, for the last six months, been unable to use my
glazier's tools, and the formation of glass knobs, for whom,
in consequence of the want of protection, certain firms, such as
the glass works of Mr. and Mrs. the following is a full and exact
list of the contractors and operators of glass knobs at
present.

has both an upper & a lower flap, prepared as cold in a metal
and are made of any figure or pattern. They are made by plac-
ing the patterned paper upon the rising from the bottom of
the mould a metallic case in which the melted glass is placed
and by pressing down the top of the mould, the metallic case is left
with a long pointed needle or aperture from the top or bottom of
the case, through which a wire or needle, rising from the bottom
of the case, holds the metallic case in place, so the pattern
is placed in the metallic case in upside with a binding wire
and the wire is made of a length of sufficient length and
is bent up the top, the wire of drawee, or can be drawn
out and bent down, so as to bring the glass flap through the wire.
